UNITED STATES PATENT OFFICE.

JOSEPH L. HILLER, OF MATTAPoisETT, MASSACHUSETTS.

METHOD FOR THE ECONOMICAL AND ADVANTAGEOUS EMPLOYMENT OF CRUSHING OR PULVERIZING MACHINES.

1,197,026.

Specification of Letters Patent.

Patented Sept. 5, 1916.

Application filed September 30, 1909. Serial No. 520,386.

To all whom it may concern:

Be it known that I, JOSEPH L. HILLER, a citizen of the United States, residing at Mattapoisett, in the county of Plymouth and State of Massachusetts, have invented new and useful Improvements in Methods for the Economical and Advantageous Employment of Crushing or Pulverizing Machines, of which the following is a specification.

10 This invention relates to a method for the economical and advantageous employment of crushing or pulverizing machines wherein the hammers or beaters are caused to rotate with high velocity in the cylinder into which the material is introduced to be reduced, such for example, as is illustrated in the Letters Patent granted to myself and George W. Borton, No. 896,019, dated August 11, 1908. Heretofore, it has been 15 the practice in the construction and use of machines of this general type, to provide what are known in the practical art, as hammer-drums, consisting of carriers fixed to rotate upon an axle and provided with 20 radially disposed pivoted hammers, and because, in actual use, the hammers wear down to a point of inefficiency, the hammer carriers or disks have been provided with several sets of perforations or openings, 25 arranged at different radial distances from the center of rotation of the drum, for attachment of the hammers, so that when the hammers become worn they may be removed and secured to the carriers or disks 30 by devices passing through a series of holes more remote from the center of rotation. This construction of the hammer-drum in the practical use of the machines results, by reason of the several sets of openings or 35 perforations in the hammer-carriers, in materially weakening such carriers with liability of breakage thereof. The construction is expensive because of the provision of the several sets or series of holes. The 40 several sets of radially disposed holes are also a source of inconvenience, because of the possibility of error of the workman in assembling the hammers. These hammer-drums comprise a very large number of 45 individual hammers, and each disk or hammer carrier has a large number of holes therein, so that there is liability of the workmen, either in initially assembling the elements of the hammer-drum, or in subsequently readjusting the hammers, becoming 50

confused, or because of carelessness, attaching some one or more series of the hammers to the carriers through the medium of inappropriate holes, necessitating waste of time in correcting the error; and when such error occurs in readjustment of the hammers to compensate for wear thereof, a material loss of work results, as it has been the practice to remove the hammer-drum from the machine for the purpose of such 60 readjustment of the hammers. In all cases the time of the workman in assembling the elements of the hammer-drum is materially increased by the necessity of accurate selection of the holes in the several sets for 65 proper attachment of the carriers. 70

By my invention, I avoid all the foregoing difficulties. I provide a plurality of machines of equal capacity wherein the cylinders within which the hammer-drums rotate, are of equal dimensions, and for said machines provide hammer-drums the hammer-carriers or disks of which are provided with but a single set or series of holes for attachment of the hammers thereto, thus 75 avoiding the weakening of the hammer-carriers by a number of sets or series of holes, as has heretofore been the practice, and also 80 economizing in the manufacture of such hammer-carriers. The series of holes in the 85 hammer-carriers in each hammer-drum, however, are arranged at different distances from the center of rotation of the hammer-drum. This may be accomplished by having the hammer-carriers of each hammer-drum of the same diameter, but with the 90 single series of hammer-attaching holes therein arranged at different radial distances from the center of rotation and at different radial distances from the circumference of the disks or carriers, or by providing hammer-drums the hammer carriers whereof are of different diameter and the single set of hammer-attaching holes of 95 which are the same distance from the peripheral edge or circumference but at different distances from the center of rotation. I prefer the latter construction, and have 100 illustrated my invention as so embodied. In addition to avoiding weakness of the 105 hammer-carriers or disks, and securing economy of manufacture thereof by the provision of a single set or series of hammer-attaching openings, my invention enables the elements of the hammer-drums to 110

be assembled quickly and accurately, as there is no room for error of the workman, such as has been above indicated, and the interchange or substitution of the hammers in the several machines may be quickly effected with a minimum interruption of the use of the machine.

The invention is illustrated in the accompanying drawings, wherein I have illustrated its carrying out by a set of three machines whereof the carriers of the hammer-drums are of different diameter, the single set of hammer-attaching holes whereof are at different distances from the center of rotation of the hammer-drum.

In said drawing, Figure 1 is a view partly in section, and partly in elevation, showing a machine provided with a hammer-drum, the hammer-attaching holes of which are relatively near the center of rotation of the hammer-drum. Fig. 2 is a view showing a cylinder conventionally, and a hammer-drum the hammer-carriers of which are of greater diameter than the hammer-carriers of the hammer-drum illustrated in Fig. 1, and the single set of hammer-attaching holes of which are at greater distance from the center of rotation than the set of holes shown in Fig. 1, and the hammers whereof are of less length than the hammers shown in Fig. 1. Fig. 3 is a view similar to Fig. 2 wherein the hammer-carriers of the hammer-drum are of still greater diameter, and the hammer-attaching holes whereof are arranged at still greater distance from the center of rotation of the hammer-drum, the hammers of which are of correspondingly less length.

Referring now to said drawing, the cylinder of the machine, as usual, consists of a pivoted grinding surface or cage 1, and a top or cover section 1^a, but my invention is not limited to machines having a cylinder of this particular type. The cylinders in the several machines shown in the drawings are of equal diameter or dimensions.

2 designates the hammer-drum shafts of the machines. The machines illustrated are provided with hammer-drums consisting of hammer-carriers (designated 3 in Fig. 1) connected for rotation with the shaft 2, as by means of keys 7, and provided with a single set of hammer-attaching holes arranged at a predetermined radial distance from the center of rotation of the hammer-drum, dependent upon the diameter of the cylinder and the length of the hammers, so that the free ends of the hammers may rotate in the proper path with relation to the cylinder for effecting the grinding or crushing. The hammers are designated by the numeral 5, and are provided at their inner ends with holes 6 adapted to be brought into register with the holes 4 of the hammer-carriers 3, and pivotally secured thereto by

means of rods or bolts 8 which pass through the registering holes in the several hammer-carriers. The carriers and hammers and the shafts by which they are carried, make up the composite hammer-drum.

The numeral 3^a designates the hammer-carriers of the hammer-drum adapted and proportioned for the machine shown in Fig. 2, which hammer-carriers are of greater diameter, and the hammer-attaching holes whereof are arranged at a greater distance from the center of rotation of the hammer-drum, dependent upon the degree to which the hammers initially employed in the machine of Fig. 1, after they have become inefficient for the purpose of the machine shown in said Fig. 1, have been reduced and dressed for use in the machine shown in Fig. 2, so that the free ends of the hammers will rotate in a proper path for efficient grinding in the latter. For convenience the reduced hammers of the hammer-drum shown in Fig. 2 are designated by the numeral 5^a.

3^b designates the hammer-carriers of the hammer-drum for the machine shown in Fig. 3, and these hammer carriers are of greater diameter, and the hammer-attaching holes therein are arranged at greater distance from the center of rotation of the hammer-drum than the corresponding parts shown in Fig. 2, and the hammers 5^b attached thereto are of less length than those illustrated in Fig. 2, depicting the degree of reduction in the length of said hammers after they have become inefficient for use in the machine shown in Fig. 2, and have been removed from the hammer-drum of that machine, dressed and incorporated as elements of the hammer-drum shown in Fig. 3.

In practising my invention employing three machines, which number I have adopted for convenience of explanation, when the hammers of the hammer-drum shown in the machine of Fig. 1, have become worn to the point of inefficiency for use in said machine, the hammer-drum may be removed from said machine, the hammers detached therefrom, preferably reduced in length and dressed to the proper degree and attached to the hammer-carriers of the machine shown in Fig. 2 having larger-hammer-carriers or the hammer-attaching holes of which are arranged at greater distance from the center of rotation, and new hammers of full length incorporated with the hammer-carriers 3, for use in the machine shown in Fig. 1; and so, likewise, when the hammers of the hammer-drum shown in Fig. 2 have become worn to the point of inefficiency for use in that machine, the said hammer-drum may be removed therefrom, the hammers detached, reduced, dressed and incorporated as elements of the hammer carriers of the machine shown in Fig. 3, and this practice may be

extended throughout a large number of machines.

The practice of the described method enables the employment of hammer-drums the carriers of which are of maximum strength, of less expense than those heretofore utilized, and the elements of which may be quickly and accurately assembled, either initially or for the purpose of interchange, because it is necessary to have only a single set of hammer-attaching holes.

The method is also capable of being carried out in the operation of a single machine by providing in the complement of the machine several sets of hammer-drums, the hammer-attaching holes of the carrier or disk whereof are arranged at different distances from the center of rotation of the hammer-drums, in which carrying out, again referring to the figures of the drawings for convenience, when the original length hammers shown in Fig. 1, are worn to the point of inefficiency the hammer-drum may be removed, the hammers detached, reduced in length, dressed and then attached to the hammer-carriers or disks 3^a of Fig. 2, having holes arranged at greater distance from the center of rotation, and this hammer-drum introduced into the machine shown in Fig. 1, and again when the hammers of this hammer-drum become worn to the point of inefficiency, said drum may be removed, the hammers detached, reduced and secured to the hammer-carriers 3^b illustrated in Fig. 3, having attaching holes arranged at still greater distance from the center of rotation, and this drum then introduced in the machine shown in Fig. 1.

Having thus described the invention, what is claimed is,—

1. The method of employment of crushing

and pulverizing machines of the rotating hammer type in which the hammers rotate in a crushing cylinder, which consists in periodically removing the hammers from carriers having attaching means located at one distance from the center thereof, and attaching them to carriers provided with attaching means located at a greater distance from the center thereof, and introducing the same into a crushing cylinder for operation with the active crushing ends of the hammers sustaining the same relation to the crushing cylinder as originally.

2. A crushing or pulverizing plant consisting of a series of two or more units, each of said units comprising a crushing cylinder, a rotating hammer carrier and hammers pivotally carried thereby, said hammer carriers provided with means for attachment of the hammers so located that said hammers are capable of being interchanged, as they become worn, from the first unit in said series through the succeeding unit or units of the series with their tips in the same relation to the crushing cylinders of each unit.

3. A crushing or pulverizing plant, consisting of a series of two or more units, each of said units comprising a crushing cylinder, a rotating hammer carrier and hammers pivotally carried thereby, with the pivotal connection of said hammers increasing in distance from their axis of rotation in each succeeding unit of said series.

In testimony whereof I have hereunto set my hand in presence of two subscribing witnesses.

JOSEPH L. HILLER.
